UNITED STATES PATENT OFFICE.

LARRY BRENNEN, OF WEST SUPERIOR, WISCONSIN.

DEVICE FOR LOCATING SUNKEN VESSELS.

SPECIFICATION forming part of Letters Patent No. 650,298, dated May 22, 1900.

Application filed December 18, 1899. Serial No. 740,432. (No model.)

To all whom it may concern:

Be it known that I, LARRY BRENNEN, a citizen of the United States, residing at West Superior, in the county of Douglas and State 5 of Wisconsin, have invented certain new and useful Improvements in Devices for Locating Sunken Vessels; and I do declare the following to be a full, clear, and exact description of the invention, such as will enable others skilled in the art to which it appertains to 10 make and use the same, reference being had to the accompanying drawings, and to the letters of reference marked thereon, which form a part of this specification.

15 This invention relates to new and useful improvements in devices for locating wrecked or sunken vessels, and especially to a buoy carrying a reel, to which is secured one end of a cable which is wound upon the reel, the 20 other end of the cable being adapted to be attached to the sunken vessel, said buoy adapted to be carried on board the ship or vessel and in case of the sinking of the latter to float to the surface of the water and display a flag 25 or signal, whereby the buoy may be easily detected.

Another feature of the invention resides in the provision of a buoy adapted to be carried in a vessel and having cable connection, 30 whereby the buoy is allowed to rise to the surface of the water, and the provision of a flag or signal staff to which is connected an air-chamber adapted to rise and cause the flag or signal staff to be raised up through a 35 central aperture in the buoy as water enters the latter and comes in contact with said air-chamber.

To these ends and to such others as the invention may pertain the same consists, further, 40 in the novel construction and arrangement of the buoy, as will be hereinafter more fully described and then specifically defined in the appended claims.

My invention is clearly illustrated in the 45 accompanying drawings, which, with the letters of reference marked thereon, form part of this application, and in which—

Figure 1 is a side elevation of a buoy shown as floating on the surface of a body of water 50 with the flag or signal displayed at its upper end; and Fig. 2 is a central longitudinal sectional view showing the detail construction of

the buoy, the flag or signal being in its closed relation within the buoy.

Reference now being had to the details of 55 the drawings by letter, A designates the shell of the buoy, which is preferably of metal of any suitable kind, and an air compartment or chamber B is provided in the upper end of said buoy, the latter having tapered ends, as 60 shown. Said air-chamber B is separated from a water-compartment C by means of a partition-wall D, said partition-wall being upwardly turned, as shown in Fig. 2 of the drawings, and having connected thereto a 65 dome E, which is secured air-tight to said partition. Leading from the upper apertured end of said dome centrally and longitudinally through the air-chamber B is an open-ended tube H, which opens at its upper end through 70 an aperture at the apex of the beveled or tapering top of the buoy. Mounted in said water-compartment C is an air-tight receptacle or float K, which has secured to its inner bottom wall a socket member K', in which is fitted the 75 lower threaded end of the stem L, which passes air-tight through an aperture at the upper end of said float K and passes vertically through the pipe H, as shown clearly in the drawings. Secured to the upper end of 80 said stem is a flag or signal M, which in Fig. 2 is shown as rolled about the upper end of the stem, but when the flag is raised from its position within the buoy is allowed to open out and assume the position shown in Fig. 1 85 of the drawings, thus displaying the flag a suitable distance above the top of the buoy to catch the eye of an observer.

Mounted near the end of the buoy in suitable bearings is a shaft N, to which is secured 90 a reel R, to which one end of a wire T is connected, said wire adapted to be wound about the circumference of the reel and its opposite end designed to be securely anchored to any portion of a ship on which the buoy is carried 95 and which it is desired to locate in case the same should sink. Said rope or cable T passes through an aperture at the lower tapering end of the buoy, said aperture being sufficiently large to allow water to enter the same when the 100 buoy becomes submerged. The water entering the lower end of the buoy and rising in the water-chamber C will cause the float K to rise to its highest limit, as shown in dotted

lines in Fig. 1 of the drawings, and in rising the stem connected to the float will be forced upward and the flag or signal displayed, as will be readily understood.

5 It will be observed that the partition D is so positioned in the buoy as to produce a sufficient air-chamber above the same, so that a conspicuous portion of the buoy will rise above the surface of the water. As the buoy 10 rises to the surface of the water the rope or cable upon the reel will unwind, and the buoyancy of the device will cause the buoy to rise to the surface of the water and assume a position relative to the said surface, substantially as illustrated in the drawings.

15 What I claim to be new, and desire to secure by Letters Patent, is—

1. In a buoy for locating sunken vessels, a float mounted in a water-compartment of the 20 buoy adapted to be raised by the water, a stem to said float having a flag at its upper end which is adapted to be normally held in a central tube in the buoy, and raised out of said tube as the float is raised by the water 25 entering the water-compartment, as set forth.

2. In a device for locating sunken vessels, a buoy having an air-chamber at its upper end, a water-compartment beneath said chamber, a float having a stem passing through a central, longitudinal pipe or passage-way opening through an aperture at the apex of the 30 buoy, a flag or signal mounted on the upper end of said stem, and normally held in said passage-way, adapted to be raised out of the

buoy as water enters the water-chamber, and 35 a reel mounted in suitable brackets at the lower end of the buoy, a cable secured to said reel, and wound thereon, the opposite end of the cable adapted to be anchored to the sunken vessel, and to unwind as the buoy rises to the 40 surface of the water.

3. A device for locating sunken vessels, consisting of a metallic buoy having a partition preferably below its middle portion and upwardly bent, a dome secured to the upper 45 end of the partition, an open-ended tube connected at its lower end to and communicating with the dome, its upper end opening through an aperture at the apex of the buoy, a float consisting of an air-tight compartment, a stem 50 secured therein, said float conforming to the shape of said dome, and to be seated therein when at its highest throw, said stem passing through an open-ended pipe and a flag or signal carried at the upper end of said stem, a 55 reel mounted at the lower end of the buoy, and a cable secured at one end to said reel, wound about the latter and passing through an aperture at the lower tapering end of the buoy and adapted to be anchored to the sunken vessel, as shown and described.

In testimony whereof I affix my signature in presence of two witnesses.

LARRY BRENNEN.
